J. L. FOLSOM.
CARPET.

No. 19,009.

Patented Apr. 9, 1889.

UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 19,009, dated April 9, 1889.

Application filed March 7, 1889. Serial No. 302,341. Term of patent 3½ years.

To all whom it may concern:

Be it known that I, JAMES L. FOLSOM, a citizen of the United States, residing in Brooklyn, county of Kings, State of New York, have 5 invented a new and original Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face 15 view of a carpet showing my new design.

My design contains a large irregular curved stem-work. Branches, mainly scroll-shaped, project therefrom, and various ornamental figures and conventionalized flower and leaf forms are attached to or constitute these 20 branches. Small inclosed portions contain damask-work of various kinds.

What I claim as new, and desire to secure by Letters Patent, is—

The design for carpets, consisting of the de- 25 sign substantially as shown.

JAS. L. FOLSOM.
